Primary Examiner — Keli L Hill*Assistant Examiner* — Karra S Johnson(74) *Attorney, Agent, or Firm* — Jeffrey P. Calfa; Mark C. Bach(57) **CLAIM**

The ornamental design for a truck vehicle, as shown and described.

DESCRIPTION

FIG. 1 is an isometric view of a truck vehicle showing our new design;

FIG. 2 is a top plan view thereof;

FIG. 3 is a left side view thereof;

FIG. 4 is a right side view thereof;

FIG. 5 is a front view of FIG. 1; and,

FIG. 6 is a back view of FIG. 1.

The broken lines shown are included for the purpose of illustrating portions of the truck vehicle that form no part of the claim. In FIG. 6, the components visible on the left, right, top, and bottom sides of the grille feature, and additional components existing above the fender feature on the left and right sides, form no part of the claim.
